UNITED STATES PATENT OFFICE

VICTOR J. EMERY, OF ALHAMBRA, CALIFORNIA

HONE OR GRINDER

Application filed November 24, 1925. Serial No. 71,121.

My invention is a hone or grinder for cylinders and is constructed to allow expansion but to prevent contraction of the honing or grinding elements.

5 An object of my invention is to provide a hone or grinder for use in cylinders or engines, in which a plurality of longitudinally spaced honing or grinding elements are carried by a supporting structure, these elements 10 are moved outwardly to the proper diameter to fit a particular cylinder and are under a spring tension tending to force said honing elements outwardly.

Another object of my invention is to trans- 15 mit the driving or rotating force in the hones at substantially their mid length in order to prevent the honing device from enlarging the mouth of the cylinder but causing it to maintain the walls absolutely parallel and there- 20 fore remain a true cylinder.

A further object of my invention is to provide a honing device for cylinders with a cage or micrometer adjustment so that when the hone is introduced into the cylinder with 25 the honing elements bearing thereagainst, the micrometer screw may be adjusted to allow grinding or honing to a certain definite larger diameter.

In my invention I utilize a hollow central 30 stem having a universal joint in the central position of the hone and having the driving spindle operating through the universal joint. A plurality of fingers are rigidly mounted on the stem. A cage surrounds the 35 stem having an upper and a lower end and with the grinding elements mounted in longitudinally extending boxes, these boxes being positioned between the cap and base ends of the cage. A spring is coiled on the lower portion 40 of the stem and engages the base of the cage and the stem, being normally tensioned to rotate the fingers and cage relative to each other so that the fingers engaging pivoted arms carrying the boxes for the grinders normally thrust these outwardly, causing a pressure 45 against the cylinder being honed.

Another feature of my invention is the placing of a stop element on the cap of the cage and utilizing a split collar on the stem, 50 this collar having a micrometer screw so that

after the collar has been set against the stop the micrometer screw may be operated to slightly displace the collar when it may be clamped and the micrometer screw then threaded back allowing the honing elements 55 to grind to the increased diameter for which the sleeve has been set.

My invention will be more readily understood from the following description and drawings, in which;

Figure 1 is a vertical elevation of my hone indicated as inserted in a cylinder.

Fig. 2 is a plan view of the hone in the direction of the arrow 2 of Fig. 1.

Fig. 3 is a base view of the hone taken in 65 the direction of the arrow 3 of Fig. 1.

Fig. 4 is a side elevation of the hone removed from the cylinder and collapsed by pressure on the honing elements.

Fig. 5 is a plan taken in the direction of the 70 arrow 5 of Fig. 4.

Fig. 6 is a vertical section indicating the hone expanded.

Fig. 7 is a transverse section on the line 7—7 of Fig. 1, taken in the direction of the 75 arrows.

Fig. 8 is a base view of the hone in the direction of the arrow 8 of Fig. 4.

Fig. 9 is a transverse section of the hone 80 on the line 9—9 of Fig. 4, or the line 9—9 of Fig. 1, with the honing elements collapsed.

A cage for supporting the honing elements is indicated by the numeral 1 and has a plurality of side longitudinal bars 2 supporting a cap 3 at the top and a base 4 at the bottom. The cap is circular as shown in Figs. 2 and 5, whereas the base has right angular cut out sections 5 to accommodate the base of the grinding arms and the grinders. This cage is preferably made as one piece or side bars 85 may be attached to the cap and to the base. The cage is a rigid structure.

The grinder supporting arms 6 are pivoted to pivot pins 7 and 8 at the base and cap and are mounted to swing outwardly. The arms have boxes 9 secured at their outer edge, such boxes extending longitudinally of the arms and grinding elements 10 are inserted in the boxes. These grinding elements are coated 95 with the honing preparations for honing or 100

grinding the cylinder. In the construction shown I utilize three pivoted arms but the number may be increased if desired.

The cam fingers 11 are integral with a hub 12, this hub having a sleeve 13 fixed to the reduced portion 14 of the stem 15 which has a hollow upper portion 16. The lower portion of the stem is screw threaded as indicated at 17 and the base has a recess 18 to 10 accommodate the nut 19 holding the stem securely to the cage but allowing slight turning movement.

A pin 20 is utilized to fasten the sleeve 13 and thus the fingers rigidly to the stem to 15 be actuated thereby. A coil spring 21 is wound on the sleeve and has one end 22 engaging the base 4 an upper end 23 engaging the hub 12 of the fingers. This spring is tensioned to normally rotate the fingers in 20 a clockwise direction.

The fingers are provided with a cam surface 24 to engage with flat machined surfaces 25 on the back of the arms. These machined surfaces on the arms are formed on inwardly 25 extending ribs 26, thus the normal tendency of the spring is to rotate the stem and cam fingers relative to the cage and the surface of the fingers bearing against the plane or machined surfaces of the ribs 26 to force the 30 arms outwardly and thus the grinding elements tightly against the cylinder.

It will be noted that the arms have a slight cut out portion 27 as shown in Fig. 9 to allow the points 28 of the fingers to fit therein when 35 the hone is collapsed by being pressed inwardly.

The driving arrangement for my hone is indicated particularly in Figs. 1, 4 and 6. A driving spindle 29 extends downwardly into 40 the hollow portion of the stem 15 and by means of a universal joint 30 is secured to the stem as close to the expanding fingers as possible, in order to have a center drive.

For purposes of illustration the universal 45 joint is shown positioned slightly above the inner end 31 of the hollow stem, but this would be placed slightly lower in order that the driving force would be substantially mid position between the upper and lower ends 50 of the grinding elements. The universal joint is indicated as having swivel pins 32 connected to the stem 15 and engaging a collar 33, and a pin 34 passes transversely through the spindle and through the collar 55 this being a simple form of universal joint.

My gauging device for indicating the amount of grinding is constructed substantially as follows, being illustrated particularly in Figs. 1, 2, 4 and 5.

A split collar 35 is mounted on the upper portion of the stem 15 above the cap 3 and has a pair of lugs 36 with a screw bolt 37 extending therethrough to clamp the split 60 collar firmly to the stem. A stop lug 38 ex-

tends upwardly from the cap, being secured thereto in any suitable manner or formed integral with the cap. A gauge lug 39 is formed integral with the split collar, preferably opposite the lugs 36. A micrometer screw 40 operates through the gauge lug 39.

It will be noted that the arms and the grinding elements supported thereby are completely below the cap 3, as clearly shown in Figs. 1, 4 and 6 and also that these arms 75 extend to the lower end of the base as shown in the same figures. The cut out sections 5 of the base allow the arms to extend downwardly into the plane of the base as shown in Figs. 3 and 8.

The operation and manner of use of my cylinder hone is substantially as follows:

It will be understood that the spindle 29 may be connected to any suitable type of driving shaft, these being usually flexible 85 shafts. When the hone is inserted in a cylinder, for instance as shown in Figs. 1 and 2, the spring forces the cam fingers 11 to rotate in a clockwise direction and hence forces the fingers with the grinding elements 90 supported thereby firmly against the cylinder walls and to properly center the hone. The bolt 37 of the split collar is loosened so that the collar may be positioned with the gauge lug in contact with the stop 38 95 on the cap. The micrometer screw 40 is then adjusted by screwing it into the gauge lug 39, the requisite distance to separate the gauge lug from the stop 38. The bolt 37 is then screwed tight clamping the split collar rigidly to the stem 15. The micrometer screw 40 is then retracted so that the gauge lug and stop lug may contact in the process of grinding as hereunder described.

It will be understood that the micrometer 105 screw may be graduated so that an operator may be able to ascertain by the number of degrees through which it is turned and the number of complete turns, how many thousandths of an inch the hone is set for grinding 110 larger than the cylinder in which it has been adjusted.

The grinding operation is carried on in the usual manner by the spindle being rotated and at the same time the hone being 115 moved longitudinally in the cylinder, thus uniformly honing and grinding the cylinder from top to bottom and giving a resultant cylindrical cylinder. As the spring forces the fingers to rotate relative to the cage and thus forces the arms outwardly, the grinding or honing will continue until the gauge lug 39 comes into contact with the fixed stop lug, thus limiting any further grinding or honing action.

It will thus be seen that with my hone the driving force is substantially mid position in regard to the length of the honing elements and thereby eliminates the danger of the cylinders being formed bell mouth and that 130

a positive gauge is provided which will allow grinding until the desired new diameter is reached and form an absolute limit to the grinding so that a cylinder cannot be over-ground.

It will be obvious that my hone or grinder may be considerably changed in general features and in specific details, such changes may be made for use in special cylinders or other requirements. These changes will be within the spirit of my invention as set forth in the description, drawings and claims.

Having thus described my invention, what I claim is:

1. A cylinder grinder comprising in combination a cage having longitudinally extending grinding elements, said elements being movable inwardly and outwardly, a driving spindle operatively connected to said

cage by a universal joint, said joint being wholly connected at substantially the mid-length of the cage.

2. A cylinder grinder comprising in combination a cage having a plurality of arms pivotally mounted to swivel outwardly of the cage, the axes of the swivelling arms being parallel to the axis of the cage, a driving spindle having a universal joint, and means operatively connecting the universal joint to the cage, the complete universal joint being positioned substantially the mid-length of the cage.

3. A cylinder grinder comprising in combination a cage having a cap and a base, a plurality of longitudinal side bars connecting the cap and the base, a plurality of arms pivotally mounted in the cap and the base, the pivotal connection being inside the said bars, grinding elements supported by the arms, a stem extending centrally through the cap and the center of the cage and being secured to the base to allow relative rotation of the cage and the stem, a plurality of cam fingers rigidly connected to the stem, having cams thereon at substantially the mid-position of the cage, the said arms having surfaces at their mid-position axially of the cage to be engaged by the said cams, a coil spring wound over part of the stem and connected to the base, and operatively connected to the fingers, adapted to normally rotate the fingers relative to the cage to cause the outward swinging of the said arms, and means to rotate the stem.

4. A cylinder grinder as claimed in claim 3 in which the stem is hollow at its upper end, having a driving spindle extending therein and with a universal joint at the lower end of the spindle said joint being connected to the stem at substantially the mid-position of the cage.

5. In a cylinder grinder, a cage having a plurality of grinding elements movable outwardly from the cage for grinding operations, a stem fitting in the cage and oper-

ative means between the stem and the grinding elements to allow outward movement of the grinding elements on partial rotation of the stem relative to the cage, a gauge comprising elements mounted respectively on

70

the stem and the cage, adapted to allow setting of the stem and the cage whereby a predetermined relative rotation may be had and a predetermined movement of the grinding elements may be obtained, the said cage being provided with a stop lug and the stem with an adjustable collar having a gauge lug to contact with the said stop lug, a micrometer screw fitted in the gauge lug to separate the gauge and stop lugs a predetermined amount by engaging the stop lug, and means to clamp the collar to the stem.

75

6. In a cylinder grinder having a structure with a plurality of expandible grinding elements mounted therein, a central stem having a driving means for rotating the said structure, the stem and the structure having a relative rotary movement, a stop lug mounted on the structure, a collar having a gauge lug mounted on the stem, a micrometer screw in the gauge lug to separate the said lug and the stop lug a predetermined amount by contacting with the stop lug and means to clamp the collar to the stem.

80

7. A hone or grinder comprising in combination a stem having a hollow upper portion, a reduced lower portion with a sleeve on the reduced lower portion and a hub on the upper end of the sleeve below the hollow portion of the stem, a cage, means mounting same on the upper and lower portions of the stem, arms pivotally connected to the upper and lower portions of the cage and having grinding elements extending longitudinally of the cage, cam fingers connected to the hub, interengaging means between the cam fingers and the arms, a driving spindle extending into the hollow portion of the stem and being connected to same by a universal joint, said joint being positioned substantially at the mid length of the cage, and a spring surrounding the sleeve interconnected between the hub and the lower portion of the cage.

95

8. A cylinder grinder comprising in combination a cage having longitudinally extending grinding elements, a stem mounted in the cage, the upper portion of said stem being hollow, a spindle extending into the hollow upper portion of the stem and being connected to same by a universal joint, said universal joint being completely positioned at substantially the mid-length of the cage.

100

9. A cylinder grinder comprising in combination a cage having a plurality of arms pivotally mounted to swing outwardly of the cage, the axes of the swinging arms being parallel to the axis of the cage, a stem mounted in the cage, the upper part of said

105

110

115

120

125

130

stem being hollow, a driving spindle extending into the hollow portion of the stem and being connected thereto by a universal joint, the said joint being completely positioned substantially the mid-length of the cage.

- 5 10. A cylinder grinder comprising in combination a cage having longitudinally extending grinding elements, a stem mounted in the cage, the upper portion of said stem being hollow, swivel pins connected to opposite sides of the hollow stem, a collar mounted on said swivel pins, a spindle extending into the hollow portion of the stem and into the collar and being pivotally connected to 15 the collar by a pin, the said swivel pins, the collar and the pin forming a universal joint, substantially on the same horizontal plane, and being connected to the hollow part of the stem substantially the mid-length of the 20 cage.

11. A cylinder grinder comprising in combination a cage having a plurality of arms pivotally connected thereto, said arms being pivoted to the top and bottom of the 25 cage and adapted to extend outwardly from the cage, a stem centrally positioned within the cage, the upper portion of said stem being hollow, a driving spindle extending into the stem, being connected thereto by a universal joint, said joint being at substantially the mid-position of the cage, a plurality of cam fingers having means rigidly connecting same to the stem at substantially the mid-position of the cage, said fingers engaging 30 the arms at substantially the mid-length of the arms considered longitudinally of the cage, a spring normally tensioned to turn the stem relative to the cage and to move said fingers into engagement with the arms, a collar adjustably mounted on the stem above the cam, the cap having a stop lug and the collar having a gauge lug, a micrometer screw extending through the gauge lug and being adapted to engage the stop lug, and means 35 to clamp the collar to the stem.

40 In testimony whereof I have signed my name to this specification.

VICTOR J. EMERY.
